UNITED STATES PATENT OFFICE

103,447

DESIGN FOR A DRESS

Tora Coleman, New York, N. Y., assignor to Alexander S. Gross, Inc., New York, N. Y., a corporation of New York

Application December 8, 1936, Serial No. 66,388

Term of patent 3½ years

To all whom it may concern:

Be it known that I, Tora Coleman, a citizen of Latvia and a resident of the Borough of Manhattan, city of New York, county of New York, and State of New York, have invented a new, original, and ornamental Design for a Dress, of which the following is a specification, reference being had to the accompanying drawing, forming part thereof, wherein

The diagonal lines represent a band of a plurality of strips in alternating contrasting colors extending diagonally from shoulder to hem.

I claim:

The ornamental design for a dress as shown and described.

TOURA COLEMAN.
